(57) **CLAIM**

The ornamental design for an outer mirror for an automobile, as shown and described.

DESCRIPTION

FIG. 1 is a front perspective view of an outer mirror for an automobile of my design;

FIG. 2 is a front view thereof;

FIG. 3 is a left-side view thereof;

FIG. 4 is a top plan view thereof;

FIG. 5 is a bottom plan view thereof;

FIG. 6 is a right-side view thereof; and,

FIG. 7 is a rear view thereof.

A second embodiment of my design is a mirror image of the embodiment depicted.
